UNITED STATES PATENT OFFICE

EDGAR M. BOUTON, OF EAST PITTSBURGH, PENNSYLVANIA, ASSIGNEE TO WESTINGHOUSE ELECTRIC & MANUFACTURING COMPANY, A CORPORATION OF PENNSYLVANIA.

ELEVATOR-CONTROL SYSTEM

Application filed April 26, 1925, Serial No. 26,843. Renewed August 12, 1927.

My invention relates to motor-control systems and it has particular relation to such systems of control as are employed in connection with elevators, hoists and similar machines.

One object of my invention is to provide means for improving the speed regulation of an elevator motor, particularly during low-speed operation.

Another object of my invention is to provide means for securing accurate stopping of the elevator independently of load conditions.

Other objects of my invention will appear in the following detailed description.

In accordance with my invention, I employ a compound wound generator or "booster" having its armature winding in circuit with the motor armature winding under all operating conditions. This system is peculiarly adapted for elevator systems employing rheostatic control and in which speed control is normally obtained by means of resistors connected respectively in series with, and in shunt relation to the motor armature. The auxiliary generator is provided with a cumulative compound series field-winding that is effective, particularly during low-speed operation, to maintain a predetermined voltage on the motor armature and to insure proper speed regulation thereof.

My invention finds particular application in connection with systems of control of the type that is set forth in Patent No. 1,526,314 of E. M. Bouton and F. E. Lewis, dated February 17, 1925 and assigned to the Westinghouse Electric and Manufacturing Company.

My invention will be described in connection with the accompanying drawing in which,

Figure 1 is a diagrammatic representation of circuits and apparatus embodying my invention.

Figs. 2 and 3 represent, schematically, certain main connections employed in the operation of the system shown in Fig. 1.

Referring particularly to Fig. 1, a shunt motor, having an armature 1 and a shunt

field-magnet winding 2, is connected to a source of energy comprising line conductors 3 and 4. The motor may be operatively connected, for example, to an elevator car 26 and maintained at rest in its inoperative position by means of an electromagnetic brake 5. An auxiliary generator, having an armature 6 and series and shunt field-magnet windings 7 and 8, respectively, has its armature 6 connected in circuit with the elevator motor armature 1. The direction of rotation of the motor is controlled by reversing switches 9, 10, 11 and 12, in accordance with well-known practice, and a line switch 13 is also employed in a familiar manner.

A starting and speed-regulating resistor, having a plurality of sections 14, 15, 16 and 17, is connected in circuit with the motor armature 1, resistor section 17 being connected in shunt relation to the armature and sections 14, 15 and 16 being connected in series relation with the armature.

A switch 18 of the normally closed type is adapted to control the circuit of the shunt resistor 17, and, similarly, the normally open switches 19 and 20 are adapted to shunt resistor sections 14 and 15 during the accelerating period. During full speed operation, the auxiliary generator field winding 7 is shunted by a resistor 16 through a switch 21. A double-pole, double-throw switch 22 is provided for maintaining the armatures 1 and 6 in circuit during all operating periods. In case of emergency, this switch may be opened to disconnect the auxiliary generator. A knife switch 23, which is located on the car, is employed for controlling the emergency switch 22. The auxiliary generator armature 6 is driven by any suitable constant speed means, such as the illustrated direct-current shunt-type motor 24.

The motor armature 1 is operatively connected in the usual manner to a driving sheave 25 for operating the elevator car 26. A car switch 27, which is located in the elevator car, provides means for controlling the direction of motion and the speed of the elevator. Auxiliary "leveling" means, comprising switches 28 and 29, which are mounted on

the car to cooperate with a plurality of cams 30 that are mounted in the hatchway adjacent to each floor, may be employed in the usual manner to control the stopping of the elevator independently of the skill of the car operator.

The success of the leveling device depends upon its ability to maintain a predetermined low operating car-speed, independently of the car load, as is well understood, and my invention finds particular application in connection with such operation.

Upon the actuation of the car switch 27 in a clockwise direction, a circuit is established 15 for the operating coils of reversing switches 10 and 12 and line switch 13, said circuit being established through car switch contact members 31 and 32 and conductors 33 and 34, in accordance with a familiar practice.

20 The main circuit for the motor armature 1 extends from line conductor 3 through switch 13, reversing switch 12, resistors 14, 15 and 16, field winding 7, switch 22 (which now occupies its left-hand closed position), armatures 6 and 1 and reversing switch 10 to line conductor 4. A portion of the starting current traverses an armature-shunt circuit comprising resistor section 17 and switch 18, thereby affording a minimum operating speed 25 of the armature 1 as in the case of the above-mentioned patent. It is recognized, however, that the speed regulation of a motor controlled solely by resistors in the armature circuit is rather poor and, in the present case, 30 the poor regulation is compensated for by the voltage from the auxiliary generator armature 6, which is impressed on the motor armature 1, so as to compensate for the drop in potential across the shunt resistor 17. The 35 auxiliary generator is so connected that the voltage from line conductors 3 and 4 and the voltage derived from the auxiliary armature 6 are in the same direction, independently of the direction of rotation of the motor 40 armature 1.

45 Upon an increase of load, the current traversing the armatures 1 and 6 also traverses the series field-winding 7 and effects a corresponding increase in the excitation 50 of the auxiliary generator, thereby increasing the voltage of said generator by the required amount. Since this generator is used for the specific purpose of maintaining suitable speed regulation at low car speeds, 55 it is possible to provide therefor a field winding 7 having suitable ampere-turns corresponding to the desired operating speed.

When full car-speed is desired, the resistors 14 to 17 are excluded in the customary manner and, in addition, the series field-winding 60 65 7 is shunted by the closure of switch 21, so that during full speed operation, there is a reduction in the value of the electromotive force of generator armature 6 that is applied to motor armature 1. This regulating effect

is adequate to compensate for varying loads at full-speed operation. I am, however, more particularly concerned with the problem of maintaining a proper speed when stopping the car or during leveling periods.

If the car 26 is operated downward by a clockwise movement of the car switch 27, as previously described, and the car switch is thereafter returned to the off position to effect a stop at any desired floor, the levelling 70 switch 29 becomes effective, upon engaging cam 30 in accordance with a familiar practice, to maintain reversing switches 10 and 12 and line switch 13 closed while approaching the floor. By this means, a slow operating speed is maintained which corresponds to the first operating point of the car switch 27, since switch 29 functions to shunt the car switch contact members 31 and 32 and maintain the previously mentioned operating circuit, comprising the conductors 33 and 34. When the car has moved downward, and is substantially flush with the corresponding floor-level, the leveling switch 29 assumes the illustrated inoperative position. If, for any 80 reason, the car should overtravel, switch 28 will close to effect a reversal of motion and return the elevator to the desired position. It is found, however, that under normal operating conditions the car-speed will be so 85 controlled, in accordance with the load, that it will always stop even with the floor without the necessity of a reversal of motion.

To manually effect upward movement of the car, the car switch 27 is actuated in a 100 counter-clockwise direction to energize contact member 35 and complete a circuit through conductors 34 and 36 to energize reversing switches 9 and 11 and line switch 13. Low-speed connections are thereby effected for the upward direction of travel, and current traverses both the armatures 1 and 6 in a direction reverse to that previously traced. Therefore, the voltage derived 105 from the auxiliary generator 6 is in the proper direction to boost the voltage impressed on the motor armature 1 in accordance with an increase in the load imposed thereon.

In the event of an overhauling load, that 115 is, when the load in the elevator car tends to drive the armature 1 and cause a reverse current or current of regeneration to flow through field winding 7, the voltage impressed by the generator armature 6 is reduced to 120 compensate for the load effect and regulate the motor speed accordingly.

It has been deemed unnecessary to further illustrate and describe the usual means for effecting variable-speed control of the elevator, all of which is under the control of the car switch 27, in accordance with a familiar practice, and which forms no part of my invention. There has been described and illustrated, however, the essential features 130

of my system that pertain particularly to the control of a motor in connection with a system of the character described in the previously-mentioned patent.

5 In Fig. 2 is illustrated the main circuit connections that obtain during slow speed operation, and in Fig. 3 I have illustrated the connections corresponding to high speed operation, for one direction of travel.

6 Various modifications of my invention may occur to one skilled in the art and I desire that my invention shall be limited only in accordance with the scope of the appended claims.

7 I claim as my invention:

1. The combination with an elevator and a hoisting motor therefor, of means for controlling the speed of said motor, and an auxiliary source of energy for modifying the effect of said controlling means, manually operable means for controlling the motor circuit, and means controlled by the movement of the elevator for controlling said auxiliary source of energy.

8. 2. The combination with an elevator and a hoisting motor therefor, of rheostatic means for controlling the voltage of the motor armature, an auxiliary source of energy for regulating the voltage applied to said motor armature, manually operable means for controlling said rheostatic means, and means operable in accordance with the movements of the elevator for controlling said auxiliary source of energy.

9. 3. The combination with an elevator and a hoisting motor therefor, of means for controlling the speed of said motor, an auxiliary source of energy comprising a compound-wound generator for modifying the effect of said controlling means, manually operable means for controlling the motor circuit, and means controlled by the movement of the elevator for controlling said auxiliary source of energy.

10. 4. The combination with an elevator and a hoisting motor therefor, of rheostatic means for controlling the voltage of the motor armature, an auxiliary generator having a cumulative compound field-winding for regulating the voltage applied to said motor armature, manually operable means for controlling said rheostatic means, and means operable in accordance with the movements of the elevator for rendering said auxiliary generator effective to secure accurate stops of said elevator.

11. 5. The combination with an elevator and a hoisting motor therefor, a rheostatic means for controlling the voltage of the motor armature, an auxiliary generator having a cumulative compound field-winding for regulating the voltage applied to said motor armature, and means for excluding the series field-winding of said generator during high-speed operation of the elevator.

6. In an elevator-control system for multispeed elevators, an elevator, a hoisting motor, a source of energy therefor, means for selectively connecting said motor to said source for low-speed and high-speed operation, means for maintaining the speed of said motor constant under varying load conditions comprising an auxiliary source of energy, means for connecting said auxiliary source of energy to said motor to increase or decrease the total energy supplied to said motor in accordance with variations in the load on said motor, and means responsive to said high-speed connecting means for diminishing the effect of said auxiliary energy source during high-speed operation.

7. The combination with an elevator and a hoisting motor therefor, of a source of electrical energy, rheostatic means for selectively controlling the voltage from said source to the motor armature for low and high-speed operation, an auxiliary generator having a cumulative compound field winding, means connecting the armature and series field winding of said generator in series relation with the armature of said motor whereby the total energy supplied to said motor will vary in accordance with the load on said motor, and means operable by said high-speed connecting means for shunting said generator series field winding.

8. In an elevator-control system, an elevator operable past a floor, a hoisting motor, a source of energy therefor, means for regulating the speed of said motor under varying load conditions comprising an auxiliary source of energy to increase or decrease the total energy supplied to the motor in some direct proportion to the load on said motor and means, operable in accordance with the position of said car with respect to said floor and effective, when said elevator is a predetermined distance in advance of said floor, to connect said motor to said source and said auxiliary source, and effective, when said elevator reaches said floor, to disconnect said motor from said source and said auxiliary source.

9. In an elevator-control system, an elevator operable past a floor, a hoisting motor, a source of energy therefor, means for maintaining the normal speed of said motor constant under varying load conditions comprising a generator, means for driving said generator, means for causing the output of said generator to increase or decrease in accordance with the load on said motor, and means operable in accordance with the position of said elevator with respect to said floor and effective when said elevator is a predetermined distance in advance of said floor, to connect said motor to said source and said generator, and effective, when said elevator reaches said floor, to disconnect said motor from said source and said generator.

10. In an elevator-control system, an elevator operable past a floor, a hoisting motor, a source of energy therefor, means for maintaining the normal speed of said motor constant under varying load conditions comprising an auxiliary source of energy to increase or decrease the total energy supplied to the motor in accordance with the load on said motor, said auxiliary source of energy comprising a compound wound generator having an armature, a shunt field winding and a series field winding, means for driving said armature, means operable, in accordance with the position of said elevator with respect to said floor and effective when said elevator is a predetermined distance in advance of said floor, to connect said series field winding and said armature in series relation with said motor and said source, and to connect said shunt field winding to said first named source of energy, and effective, when said elevator reaches said floor, to disconnect said motor from said source and said auxiliary source and to disconnect said shunt field winding from said source, and means for varying the output of said generator at will.
11. In an elevator-control system, an elevator operable past a floor, a hoisting motor, a source of energy therefor, means for maintaining the normal speed of said motor constant under varying load conditions comprising an auxiliary source of energy to increase or decrease the total energy supplied to the motor in accordance with the load on said motor, means for variably determining the constant speed of said motor, and means, operable in accordance with the position of said car with respect to said floor and effective, when said elevator is a predetermined distance in advance of said floor, to connect said motor to said source and said auxiliary source, and effective, when said elevator reaches said floor, to disconnect said motor from said source and said auxiliary source.
12. In a motor-control system for an elevator; a hoisting motor; a main source of power for said motor; an auxiliary source of power for said motor effective to supply a component of voltage proportional to the load on said motor; and a controller for said motor, including means operable to control said main source of power to cause said motor to operate at a low and high speed, means responsive to operation of said controller to cause said motor to operate at a low speed for connecting said motor to said source in series with said auxiliary source to provide a slow speed for said motor the value of which is independent of the load on said motor, and means responsive to operation of said controller to cause high-speed operation of said motor to render said auxiliary source ineffective to supply said proportional component of voltage to said motor.
13. In a motor-control system for an elevator; a hoisting motor; a main source of power for said motor; an auxiliary source of power for said motor comprising a generator having a series winding effective to supply a component of voltage proportional to the load on said motor; and a controller for said motor, including means operable to control said main source of power to cause said motor to operate at a low and a high speed, means responsive to operation of said controller to cause said motor to operate at a low speed for connecting said motor to said source in series with said auxiliary source to provide a slow speed for said motor the value of which is independent of the load on said motor, and means responsive to operation of said controller to cause high-speed operation of said motor to render said auxiliary source ineffective to supply said proportional component of voltage to said motor.
14. In a motor-control system for an elevator operable past a floor; a hoisting motor; a main source of power for said motor; an auxiliary source of power for said motor effective to supply a component of voltage proportional to the load on said motor; and a controller for said motor, including means to complete and interrupt low and high-speed circuits for said motor, means responsive to completion of a low-speed circuit for connecting said motor to said main source in series with said auxiliary source to provide a low operating speed of said motor the value of which is independent of the load on said motor, means responsive to completion of a high-speed circuit to render said auxiliary source ineffective to supply said proportional component to said motor, and additional means to control said low-speed circuit, said additional means being effective to complete said low-speed circuit when said car reaches a point a predetermined distance in advance of said floor and to interrupt said circuit when said car reaches a point substantially level with said floor.
15. In a motor-control system for an elevator operable past a floor; a hoisting motor; a main source of power for said motor; an auxiliary source of power for said motor comprising a generator having a series winding effective to supply a component of voltage proportional to the load on said motor; and a controller for said motor, including means to complete and interrupt low and high-speed circuits for said motor, means responsive to completion of a low-speed circuit for connecting said motor to said main source in series with said auxiliary source to provide a low operating speed of said motor the value of which is independent of the load on said motor, means responsive to completion of a high-speed circuit to render said aux-

iliary source ineffective to supply said proportional component to said motor, and additional means to control said low-speed circuit, said additional means being effective to complete said low-speed circuit when said car reaches a point a predetermined distance in advance of said floor and to interrupt said circuit when said car reaches a point substantially level with said floor.

16. In a control system for an elevator operable past a floor; a hoisting motor; a main source of power for said motor; an auxiliary source of power for said motor effective to supply a component of voltage proportional to the load on said motor; and a controller for said motor, including leveling mechanism to effect the stoppage of said car substantially level with said floor, said leveling mechanism comprising means effective when said car reaches a point a predetermined distance in advance of said floor to connect said motor to said main source in series with said auxiliary source to provide a slow operating speed of said motor the value of which is independent of load and effective when said car reaches a point substantially level with said floor to disconnect said motor from both of said sources.

17. In a control system for an elevator operable past a floor; a hoisting motor; a main source of power for said motor; an auxiliary source of power for said motor comprising a generator having a series winding effective to supply a component of voltage proportional to the load on said motor; and a controller for said motor, including leveling mechanism to effect the stoppage of said car substantially level with said floor, said leveling mechanism comprising means effective when said car reaches a point a predetermined distance in advance of said floor to connect said motor to said main source in series with said auxiliary source to provide a slow operating speed of said motor the value of which is independent of load and effective when said car reaches a point substantially level with said floor to disconnect said motor from both of said sources.

In testimony whereof, I have hereunto subscribed my name this 20th day of April, 1925.

EDGAR M. BOUTON.
